UNITED STATES PATENT OFFICE.

MARINUS PEPLING, OF NEWARK, NEW JERSEY, ASSIGNOR TO FRED MOSS, OF NEW YORK, N. Y.

WINDING-MACHINE.

1,072,157.

Specification of Letters Patent.

Patented Sept. 2, 1913.

Application filed July 18, 1910. Serial No. 572,439.

To all whom it may concern:

Be it known that I, MARINUS PEPLING, a citizen of the United States, and a resident of Newark, Essex county, New Jersey, 5 have invented certain new and useful Improvements in Winding-Machines, (Case B,) of which the following is a specification.

My invention relates to winding machines for winding cops, of that kind in which relative reciprocation is produced between a thread guide and a winding spindle, and the successive advances of the thread are produced by friction roller means 15 to which rotary motion is imparted at intervals by the winding spindle.

The invention relates particularly to that type of such machines which wind cops on paper tubes, the cops having tapered ends 20 and a cylindrical body. The rear end of such a cop is known as the heel. The throw of the thread due to the reciprocation of the thread guide is known as the traverse, and a complete traverse may be regarded as 25 being composed of an out stroke and a back stroke.

The object of the invention is to provide a friction roller which is normally at a distance from the winding spindle, and which, 30 between traverses during the building of the heel, is moved toward the winding spindle so as to be rotated thereby, thus producing the advances for forming the heel of the cop.

A further object is to move the friction roller diminishing distances toward the spindle on the successive back strokes during the building of the heel.

Another object is to provide means for 40 causing the friction roller to approach the winding spindle on the early back strokes, which means is mounted on a stationary part, such as the frame of the machine, or independently of the reciprocating parts, 45 and is adapted to be contacted by a suitable contact member reciprocating with said parts.

A particular object of the invention is to 50 provide active heel shaping mechanism, which is mounted independently of the reciprocating parts and is actuated by the back strokes thereof to move the friction roller toward the spindle so as to be rotated thereby.

55 A further object is to simplify and im-

prove the construction and arrangement of the several parts.

With these and other objects in view, the invention consists in the constructions, arrangements and combinations hereinafter described, illustrated by the preferred embodiments in the accompanying drawings, and more particularly pointed out in the appended claims.

In the said drawings: Figure 1 is 65 an end elevation of the machine; Fig. 2 is a sectional front elevation showing the mechanism for swinging the traverse bar; Fig. 3 is a plan view of the parts in front of the frame of the machine, showing the heel of the cop partially completed and the traverse bar, friction roller and thread guide at the end of the out stroke; Fig. 4 is a similar view, but showing the reciprocating parts at the end of 70 their back stroke, with the traverse bar and friction roller swung toward the spindle and the roller contacting with the thread of the cop; Fig. 5 is a similar view, showing the heel completed and the friction roller 75 working on the partially completed body of the cop. The parts are shown at the end of the back stroke. In dotted lines are indicated the completed cop and the friction roller at the end of its final back stroke. Fig. 6 is a sectional detail, showing the 80 spring actuated incomplete nut for coupling the friction roller to the threaded traverse bar; Fig. 7 is a detail sectional view showing the fork or yoke for coupling the friction roller with the thread guide; and Fig. 8 is a detail plan view of the 85 universal joint connection between the rear end of the traverse bar and the oscillating arm for reciprocating the same.

In these drawings, the numeral 11 indicates any suitable form of frame, which in practice is considerably larger than is indicated in the drawings. On the frame is mounted a driving shaft 12. This shaft 12 90 rotates a plurality of spindles 13, projecting forward through the frame; but only one spindle is illustrated in the drawings. The shaft 12 may drive the spindle 13 by means of a bevel friction disk 15 and a bevel friction gear 16; but it is obvious that such details are immaterial.

The numeral 17 indicates a suitable form of thread guide, between which and the spindle 13 a relative reciprocation is pro- 110

duced. It is regarded as preferable to reciprocate the thread guide; and the means for effecting such reciprocation may be varied widely. In the illustrated construction, a cam-shaft 18 (driven in any suitable manner by the driving shaft 12 or otherwise) is provided with a cam 19, which oscillates a spring-supported lever 20, which in turn oscillates a rock-shaft 21, being connected with an arm 22 thereof by a link 23. An arm 24 carried by the rock shaft is connected to a traverse bar 25 and reciprocates the same. In accordance with the best form of the invention, the reciprocation of the traverse bar is imparted to the thread guide in the following manner: A friction roller 26 is mounted on the traverse bar; and this roller is shown as being provided with a collar extension 27 which is engaged by a coupling or fork 28, which fork is secured adjustably to a reciprocating rod 29 on which the thread guide 17 is adjustably mounted.

According to the best form of the invention, the thread guide is mounted independently of the traverse bar 25. To this end it is shown mounted on the rod 29, which itself is mounted for longitudinal rectilinear reciprocation, as by being received in stationary bearings 30 on the frame. Thus, by virtue of the coupling 28, the thread guide partakes of the reciprocation of the traverse bar 25, but said bar moves laterally independently of the thread guide, in the manner hereinafter described.

The roller 26 gives the successive advances to the thread guide 17 for the building of the heel of the cop. This advance is produced by screw-threaded means through the rotation of the friction roller at intervals by the winding spindle, through contact of the periphery of the roller with the thread of the building cop. In the particular embodiment of the invention illustrated, the traverse bar 25 is threaded, and the friction roller 26 is adapted to be coupled with the threads thereof; so that rotation of the roller on the traverse bar advances the roller along the bar. Through suitable connections, such as already described, the roller imparts this advance to the thread guide 17.

The roller 26 is provided with a form of quick release device, which is adapted to travel with the roller and has movement relative thereto for engagement and disengagement with the threads of the traverse bar 25. In the particular form illustrated, the device is in the nature of an incomplete nut 31, having threads extending along an arc only of its interior, as shown at 32. This nut is shown as mounted in a housing 33 on the face of the roller 26, for sliding movement in a direction transverse of the traverse bar 25. A spring 34 urges the nut into engage-

ment with the threads of the bar, and may be secured to one end of the nut and confined between said end and an abutment 35 on the face of the roller. The other end of the nut projects and affords means for manually releasing the device against the tension of the spring.

Suitable means are provided for shaping the heel of the cop, which means may be widely varied. In accordance with this feature of the invention, the traverse bar 25 and the friction roller 26 are laterally yieldable for the purpose of enabling the friction roller to be brought into frictional contact with the thread of the cop at the conclusion of each back stroke during the building of the heel of the cop. In the best form of the invention, the traverse bar is swiveled at its rear end for this purpose; being connected by universal joint connection with the arm 24. Such joint may be of various forms. As shown, the upper end of the arm 24 is provided with spaced ears 36, concave on their inner faces and having transverse slots 37, in which are received a pivot pin 38 secured to the ball end of the traverse bar 25. The bar is, thus, enabled to swing side-wise toward and from the spindle 13.

The fork 28 is swiveled, as indicated at 39, so as to cause no binding when the traverse bar 25 and the friction roller 26 are swung toward the spindle.

In accordance with the form of the invention illustrated, mechanism is mounted independently of the reciprocating parts and is actuated thereby to move the traverse bar and roller laterally between traverses. In the best construction, a bell-crank lever has a long pivot portion 40 mounted in a suitable stationary support or bracket 41; and one arm 42 of this lever is disposed in the path of an abutment or contact member 43 mounted adjustably on the shaft 29 of the thread guide. The other arm 44 of said lever is connected by a link 45 with a projection 46 on a swinging bracket 47. Said bracket 47 is pivotally supported as indicated at 48, and affords a bearing through which the traverse bar 25 slides. As will be apparent, when the abutment 43 pushes the arm 42, which is preferably inclined forward, to the rear, the traverse bar 25 and the roller 26 are moved toward the spindle 13. When the contact member 43 again moves forward, the traverse bar and the roller, and likewise the lever 42, are restored to their former positions by a spring 49, which draws the bracket 47 against an adjustable stop 50. Instead of the abutment 43, moving contact means may be provided in any suitable manner, as, for example, the fork 28 may be caused to contact with the arm 42 of the bell-crank lever.

In the operation of the invention, at the conclusions of the back strokes of the thread

distributing means during the building of the heel of the cop, the lever 42 is actuated and causes the friction roller 26 to approach the spindle 18 and thus be rotated by frictional engagement with the thread of the building cop. This rotation advances the roller and the thread guide, and also the abutment 43. Consequently, on each successive back stroke, during the building of the heel of the cop, the abutment 43 moves the lever a shorter distance, and the roller, consequently, approaches a less distance toward the spindle as the cop builds up in thickness. Finally, the abutment no longer contacts with the lever; and thereafter the roller is not advanced toward the spindle, but has rectilinear movement only. The roller 26 now proceeds to build up the cylindrical body of the cop; for this purpose, contacting on each back stroke with the high part of the cop and producing the requisite advance. In the preferred form of the invention illustrated, the roller 26 is in the nature of a thin disk, whose width is materially less than the traverse of the thread (indicated by the letter *b* in the drawing), and the thread guide 17 is located substantially opposite the center or high point of the periphery of the disk, said periphery being slightly inclined and rounded. By adjusting the stop 50, the width of the cop may be varied.

While the machine is shown as operating on a tapering spindle and cop tube, it operates as well on cylindrical spindles and tubes.

Having thus described my invention, what I claim as new, and desire to secure by Letters Patent, is:—

40 1. In a winding machine, the combination of a rotary spindle adapted to wind a cop, a thread guide, a friction roller, means for supporting the roller and for causing rotation thereof to produce an advance of the thread guide, means for producing relative reciprocation between the spindle on the one hand and the thread guide and friction roller on the other hand to effect the traverse of the thread, said roller being normally spaced laterally away from said spindle and heel shaping means operative during the building of the heel of the cop for causing said friction roller to repeatedly approach said spindle, the movement toward said spindle permitting said roller to be rotated by said spindle, and said roller returning to its normal position after each approach.

60 2. In a winding machine, the combination of a rotary spindle for winding a cop, a thread guide, a friction roller normally spaced laterally away from said spindle, means for producing a relative reciprocation between the parts to effect the traverse of the thread, heel shaping means operative

during the building of the heel of the cop for causing said friction roller to laterally approach said spindle so as to permit the roller to return to its normal position away from said spindle after each approach. 70

3. In a winding machine, the combination of a rotary spindle, a thread guide, a friction roller, means for supporting the roller and for causing its rotation to produce an advance of the thread guide, means for producing relative reciprocation between the spindle on the one hand and the thread guide and the friction roller on the other hand to effect the traverse of the thread, a stop for holding said roller normally in laterally spaced relation to said spindle during the building of the body of the cop, heel shaping means operative during the building of the heel of the cop for causing the friction roller to move successively toward the spindle to be rotated thereby, said means moving said roller toward said spindle while the roller is moving toward the back of the machine, and means operative after each of the successive movements of the roller toward the spindle to cause the roller to move away from said spindle until arrested by said stop. 80

4. In a winding machine, the combination of a rotary spindle, a thread guide, a threaded traverse bar, a friction roller mounted on the traverse bar and adapted to advance the thread guide, means for reciprocating the traverse bar and the thread guide to effect the traverse of the thread, an adjustable stop for holding said traverse bar and roller in laterally spaced relation to said spindle during the building of the body of the cop, heel shaping means operative during the building of the heel of the cop for causing said traverse bar and friction roller to move successively toward said spindle to produce the successive advances of the thread guide, and means operative after each of said successive movements of the traverse bar and roller toward the spindle to cause the same to move away from the spindle until arrested by said stop. 95

5. In a winding machine, the combination of a rotary spindle adapted to wind a cop, a thread guide, a friction roller, means for supporting the roller and for causing its rotation to produce an advance of the thread guide, means for producing a relative reciprocation between the spindle and the thread guide and friction roller to effect the traverse of the thread and heel shaping means operated during the building of the heel of the cop for causing the friction roller to repeatedly move diminishing distances toward said spindle during the building of the heel, said roller moving outward after each inward movement. 110

6. In a winding machine, the combination of a rotary spindle adapted to wind a 130

4
5 cop, a longitudinally reciprocating, laterally movable threaded traverse bar, means for reciprocating said bar to effect the traverse of the thread, a thread guide mounted independently of said traverse bar and connected therewith so as to be reciprocated thereby, a friction roller mounted on said bar and connected with said thread guide so as to advance the same, and heel shaping means operative during the building of 10 the heel of the cop for causing said traverse bar and friction roller to move successively toward said spindle to produce successive advances of the thread guide, said traverse bar and friction roller moving outward 15 after each inward movement.

6 7. In a winding machine, the combination of a rotary spindle adapted to wind a cop, a longitudinally reciprocating, traverse bar, 20 means for reciprocating said traverse bar to effect the traverse of the thread, said traverse bar being swiveled at its rear end so as to swing toward and from said spindle, a reciprocating thread guide, a friction roller mounted on said traverse bar and means whereby successive rotations of said roller progressively advance said thread guide, and heel shaping means operative between complete traverses during the building of 25 the heel of the cop for causing said traverse bar and friction roller to move successively toward said spindle to produce successive advances of the thread guide, said traverse bar and roller moving outward 30 from the spindle after each inward movement toward the same.

8 8. In a winding machine, the combination of a winding spindle, a laterally yieldable traverse bar, a thread guide, a friction 40 roller on said traverse bar and means whereby successive rotations of said roller progressively advance the thread guide, means for longitudinally reciprocating said traverse bar, thread guide and friction roller, 45 and heel shaping means mounted independently of the reciprocating parts and adapted to be contacted on the early back strokes by one thereof to cause said roller to move toward said spindle so as to be rotated 50 thereby, said traverse bar and roller moving outward from the spindle after each inward movement toward the same.

9 9. In a winding machine, the combination of a winding spindle, a laterally yieldable traverse bar, a thread guide, a friction 55 roller of a width materially less than the traverse of the thread mounted on said traverse bar, means whereby rotation of the roller produces an advance of the thread 60 guide, means for longitudinally reciprocating said traverse bar, thread guide and friction roller for effecting the traverse of the thread, and heel shaping means mounted independently of the reciprocating parts 65 and adapted to be contacted on the back

70 strokes by one thereof to cause said roller to move repeatedly toward and away from said spindle so as to be repeatedly rotated thereby to impart to said thread guide successive advances for building the heel of the cop, said roller being adapted after passing beyond the influence of said heel shaping means to build the body of the cop.

10 10. In a winding machine, the combination of winding means including a rotary 75 spindle, thread distributing means including a thread guide and a friction roller, means for reciprocating one of said means, means for supporting the roller and causing rotation thereof to advance the thread guide, 80 and heel shaping mechanism mounted independently of the reciprocating means and actuated on the early back strokes by one thereof for causing said friction roller to move repeatedly toward and from said spindle so as to be repeatedly rotated 85 thereby.

11 11. In a winding machine, the combination of a winding spindle, a thread guide, a friction roller, means for supporting the 90 roller and for causing rotation thereof to advance the thread guide, means for reciprocating the thread guide and friction roller, and heel shaping mechanism mounted independently of the reciprocating parts 95 and adapted to be actuated by one thereof on the early back strokes to cause said friction roller to move repeatedly toward and from said spindle so as to be repeatedly rotated thereby.

12 12. In a winding machine, the combination of a winding spindle, a thread guide, a friction roller, means for reciprocating the thread guide and friction roller, means for supporting the roller and for causing rotation thereof to advance the thread guide, and a heel shaping lever adapted to be actuated on the early back strokes of the reciprocating parts by one thereof for causing said friction roller to repeatedly approach 110 and recede from said spindle so as to be repeatedly rotated thereby.

13 13. In a winding machine, the combination of a winding spindle, a thread guide, a friction roller, means for supporting the 115 roller and for causing rotation thereof to advance the thread guide, means for reciprocating the thread guide and friction roller, and heel shaping mechanism including a yielding member in the path of a reciprocating part adapted to be actuated thereby on the early back strokes thereof to cause said friction roller to move repeatedly toward and from said spindle so as to be repeatedly rotated thereby.

14 14. In a winding machine, the combination of a winding spindle, longitudinally reciprocating parts including a traverse bar which is also laterally yieldable, a friction roller thereon, a thread guide, and means 130

whereby rotation of the roller causes the thread guide to advance a contact part, and heel shaping mechanism mounted independently of said reciprocating parts and including a member in the path of said contact part, whereby said mechanism is actuated by said contact part on the back stroke thereof to cause said traverse bar and friction roller to approach said spindle to rotate said roller, said traverse bar and roller moving outward from the spindle after each inward movement toward the same.

15. In a winding machine, the combination of a winding spindle, a laterally yieldable, longitudinally reciprocating threaded traverse bar, a friction roller thereon, a thread guide carrier adapted to be reciprocated by said bar and advanced by said roller, means supporting said carrier independently of said traverse bar, a thread guide on said carrier, a contact part on said carrier, and mechanism connected with said traverse bar for causing said traverse bar and friction roller to move repeatedly toward and from said spindle to produce the successive advances of the thread guide, said mechanism including a movable member in the path of said contact part.

16. In a winding machine, the combination of a winding spindle, a laterally yieldable, longitudinally reciprocating traverse bar, a friction roller thereon, and means whereby rotation of the roller produces forward movement thereof, a thread guide and contact part adapted to be advanced by said friction roller, a laterally movable bearing in which said traverse bar reciprocates, and automatic mechanism for moving said bearing including a motion transmitting member in the path of said contact part.

17. In a winding machine, the combination of a winding spindle, a laterally yieldable, longitudinally reciprocating traverse bar, a friction roller thereon, and means whereby rotation of the roller produces forward movement thereof, a thread guide and contact part adapted to be advanced by said friction roller, a stationary support, and a bell-crank lever mounted thereon, one arm of said lever being disposed in the path of said contact part and the other arm being connected with said traverse bar, whereby said friction roller is moved toward said spindle at the concluding portions of the early back strokes of the traverse bar.

18. In a winding machine, the combination of a winding spindle, a thread guide, a friction roller, means whereby rotation of the roller advances the thread guide, means for reciprocating the thread guide and roller to effect the traverse of the thread, and heel shaping mechanism mounted independently of the reciprocating parts and actuated by one of said parts during the early back strokes to move the roller dimin-

ishing distances toward the spindle for building the heel of the cop, said roller subsequently producing the advances for building the body of the cop.

19. In a winding machine, the combination of a winding spindle, a laterally yieldable traverse bar, means for longitudinally reciprocating said bar, a friction roller having threaded engagement with said bar, means operative during the building of the heel of the cop for repeatedly moving said traverse bar and friction roller toward the spindle to secure the successive advances, means for returning the traverse bar and friction roller to normal position away from the spindle after each inward movement, a rod mounted for longitudinal rectilinear reciprocation in a stationary support, a thread guide secured to said rod, and means connecting said roller and rod whereby the latter is reciprocated and successively advanced by the former.

20. In a winding machine, the combination of a winding spindle, a laterally yieldable traverse bar, swiveled at its rear end so as to swing toward and from said spindle, means for longitudinally reciprocating said bar, said bar swinging toward said spindle during each longitudinal reciprocation, a friction roller on said bar, a reciprocating thread guide, means whereby rotation of the roller advances the thread guide and heel shaping means for repeatedly swinging the traverse bar toward and from the spindle during the building of the heel and an adjustable stop for limiting the outward swings.

21. In a winding machine, the combination of a winding spindle, a traverse bar, means for longitudinally reciprocating the same, said bar having a swivel connection with said means, a friction roller on said bar, a reciprocating thread guide, means whereby rotation of the roller advances the thread guide, heel shaping means for repeatedly moving said bar and roller diminishing distances toward said spindle during the building of the heel of the cop, said traverse bar swinging toward said spindle during each longitudinal reciprocation, said heel building means being adjustable.

22. In a winding machine, the combination of a winding spindle, a traverse bar, means for reciprocating said bar, a laterally translatable bearing in which said bar reciprocates, a friction roller on said bar, and means whereby rotation of the roller produces forward movement thereof, a reciprocating thread guide advanced by the roller, and means for laterally and bodily moving said traverse bar and bearing in conjunction with the reciprocation of the former for shaping the heel of the cop.

23. In a winding machine, the combination of a winding spindle, a traverse bar

5 pivotally supported at its rear end, means for reciprocating said bar, a pivoted hanger supporting the rear portion of said traverse bar so as to enable said bar to move toward
 10 and from said spindle, a friction roller mounted on said bar, and means whereby rotation of the roller produces forward movement thereof, a reciprocating thread guide advanced by the roller, and means for controlling the distance between said traverse bar and spindle for shaping the heel of the cop.

24. In a winding machine, the combination of a winding spindle, a traverse bar, 15 means for reciprocating said bar, a laterally movable bearing in which said bar reciprocates, a stop for limiting the movement of said bearing in one direction, a spring for urging said bearing against said stop, a friction roller mounted on said bar, and means whereby rotation of the roller produces forward movement thereof, a reciprocating thread guide advanced by the roller, and means whereby said traverse bar 20 is moved toward said spindle against the tension of said spring for shaping the heel of the cop.

25. In a winding machine, the combination of a rotary spindle adapted to wind a 30 cop, a longitudinally reciprocating, laterally yieldable threaded traverse bar, means for reciprocating the same, a friction roller and a peripherally grooved part on said traverse bar, means operative during the 35 building of the heel of the cop for repeatedly moving said traverse bar and friction roller toward the spindle to secure the successive advances, means for returning the traverse bar and friction roller to normal 40 position away from the spindle after each inward movement, a reciprocating thread guide carrier mounted independently of said traverse bar, a thread guide thereon, and a yoke secured to said carrier and engaging said groove whereby said thread 45 guide is reciprocated and advanced.

26. In a winding machine, the combination of a rotary spindle adapted to wind a cop, a longitudinally reciprocating, laterally yieldable threaded traverse bar, means 50 for reciprocating the same, a friction roller and a peripherally grooved part on said traverse bar, means operative during the building of the heel of the cop for repeatedly moving said traverse bar and friction 55 roller toward the spindle to secure the successive advances, means for returning the traverse bar and friction roller to normal position away from the spindle after each 60 inward movement, a reciprocating thread guide carrier mounted independently of said traverse bar, a thread guide thereon, a swiveled yoke secured to said carrier and engaging said groove whereby said thread 65 guide is reciprocated and advanced.

27. In a winding machine, the combination of a winding spindle and a thread guide, and means for producing relative reciprocation between the two, of a threaded traverse bar, a friction roller thereon adapted to advance said thread guide, a quick release member adapted to couple said roller to said traverse bar, said member being mounted slidably in a guide on the end face of said roller for movement into and 75 out of threaded engagement with said bar, and resilient means for holding said member in engagement with said traverse bar.

28. In a winding machine, the combination of a winding spindle and a thread 80 guide, and means for producing relative reciprocation between the two, of a threaded traverse bar, a friction roller thereon adapted to advance said thread guide, an incomplete nut inclosing said traverse bar and 85 adapted to couple said roller to said traverse bar, and a guide carried by said roller in which said nut slides transversely of said bar to release said roller therefrom.

29. In a winding machine, the combination of a winding spindle and a thread 90 guide, and means for producing relative reciprocation between the two, of a threaded traverse bar, a friction roller thereon adapted to advance said thread guide, an incomplete nut inclosing said traverse bar and 95 adapted to couple said roller to said traverse bar, said nut being mounted slidably on said roller for movement in a direction transverse of said bar to release said roller therefrom, 100 and a spring for holding said nut in threaded engagement with said bar, said nut having a projecting portion outside the roller whereby it may be moved manually in opposition to said spring.

30. In a winding machine, the combination of a rotary spindle adapted to wind a cop, a thread guide, a friction roller and means whereby rotation of the roller produces successive advances of the thread 110 guide, means for producing relative reciprocation between the spindle on the one hand and the thread guide and friction roller on the other hand to effect the traverse of the thread, and mechanism operative between complete traverses during the building of the heel of the cop for moving said spindle and roller toward and then away from each other to produce successive advances of the thread.

31. In a winding machine, the combination of a rotary spindle adapted to wind a cop, a reciprocating thread guide, a reciprocating friction disk normally spaced away from said spindle, means whereby rotation of the roller produces successive advances of the thread guide and means operative during the building of the heel of the cop at the conclusions of the back strokes of the disk to cause said disk to move diminish- 125 130

ing distances toward the spindle into contact with the thread of the cop and away from the spindle after each approach, whereby the advances are given to build the heel 5 of the cop.

32. In a winding machine, the combination of a rotary spindle adapted to wind a cop, a reciprocating thread guide, a reciprocating friction disk normally spaced away 10 from said spindle, means whereby rotation of the roller produces successive advances of the thread guide and means operative during the building of the heel of the cop at the conclusions of the back strokes of the 15 disk to cause said disk to move diminishing distances toward the spindle into contact with the thread of the cop and away from the spindle after each approach, whereby the advances are given to build the heel of 20 the cop, said disk being adapted in its subsequent reciprocations to contact with the thread of the cop to build the body thereof.
33. In a cop winding machine, having a rotary spindle, a narrow friction disk for 25 building the heel of the cop, movable repeatedly during the building of the heel toward the spindle in directions transverse thereto into contact with the thread on the spindle, said disk moving away from the 30 spindle after each motion toward the spindle.

34. In a winding machine, having a rotary spindle for winding a cop, a single friction roller for building the heel and body of 35 the cop, said roller being movable repeatedly during the building of the heel toward and

from the spindle in directions transverse to the same to be repeatedly rotated thereby.

35. In a winding machine, having a rotary spindle for winding a cop, a friction 40 roller and means for causing the same to move repeatedly toward and from said spindle in directions transverse thereto to be repeatedly rotated thereby to build the heel of the cop. 45

36. In a winding machine a rotary spindle adapted to wind a cop, a thread guide, means for producing relative longitudinal reciprocation between the thread guide and spindle to effect the traverse of the thread, a friction roller for advancing the thread, and means for producing relative lateral movement between the spindle and roller toward and from each other at intervals during the building of the heel to effect repeated rotation of the roller. 50

37. In a cop winding machine, having a rotary spindle, a friction roller for building the heel of the cop, and means for causing said roller to move repeatedly toward the 60 spindle and back to starting position during the building of the heel in directions transverse to the spindle into and out of rotative contact with the thread of the building cop.

In testimony whereof, I have signed my 65 name to this specification, in the presence of two subscribing witnesses.
